*Primary Examiner—Paula A. Mortimer
Attorney, Agent, or Firm—R. William Graham***[57] CLAIM**

I claim the ornamental design for the casket, as shown and described.

DESCRIPTION

FIG. 1 is a perspective view of a casket showing my new design with half of its lid in an open position and having shading depicting its wood structure;

FIG. 2 is a top plan view thereof;

FIG. 3 is a side elevational view thereof, the opposite side is a mirror image; and,

FIG. 4 is an end elevational view thereof, the opposite end is a mirror image.

1 Claim, 2 Drawing Sheets Fig. 1
